Phillips Abbott.

UNITED STATES PATENT OFFICE.

CHARLES H. HAWKINS, OF FREEPORT, AND CHARLES W. SMITH AND HERBERT E. SCHANZENBACH, OF NEW YORK, N. Y., ASSIGNORS TO THE STANDARD OIL COMPANY OF NEW YORK, A CORPORATION OF NEW YORK.

NIGHT-LIGHT.

1,174,934.

Specification of Letters Patent.

Patented Mar. 7, 1916.

Application filed July 3, 1915. Serial No. 38,027.

To all whom it may concern:

Be it known that we, CHARLES H. HAWKINS, a citizen of the United States, and a resident of the town of Freeport, county of 5 Nassau, and State of New York, and CHARLES W. SMITH and HERBERT E. SCHANZENBACH, citizens of the United States, and residents of the borough of Brooklyn, county of Kings, city and State of New York, have 10 jointly invented a new and useful Improvement in Night-Lights, of which the following is a specification.

As night lights have heretofore been constructed a difficulty exists which seriously 15 affects their usefulness, that is to say, the wick, which is necessarily a small, flimsy affair, composed usually of a few strands of cotton material, upon being ignited, burns for a time satisfactorily. Soon, however, 20 as the wax, or other fuel, melts about the wick, usually to a depth of about half an inch, the support it afforded to the wick when cold is removed and consequently, particularly if any considerable amount of ash 25 forms upon the wick, it topples over by its own weight and falling into the molten wax is extinguished, or if it does not topple over of its own weight, the blast of air from the mouth of one blowing out the light is very 30 apt to blow it over, resulting in the same submergence in the melted wax, with the resulting extinction. In order to obviate this difficulty, the makers of such lights have heretofore employed various means of stiffening or holding up the wick, such as a 35 thin, easily fusible wire of soft lead, or the like, which will be melted by the flame and subside into the molten wax as the wick burns. Sometimes a section of a small 40 broom or brush straw has been used for the same purpose but these devices are objectionable and unsatisfactory, because in use the molten lead or ash from the broom straw dropping in the melted wax or fuel very 45 quickly defiles it, making the night light unsightly and also the strands of the wicking, owing to their movements while burning, or air drafts, are apt to become disconnected from the support so that they are apt to fall

over or subside into the molten wax as before, with the same results. Furthermore, the introduction of the wicking into the molten wax in the first instance during the making of the light is attended with difficulty and more or less expense. It is necessary to connect the lower end of the wicking with a suitable support or anchor, usually a metal device of some sort, and the upper end of the wick has to be supported upon a removable cross bar of some sort which spans across the upper end of the receptacle forming the container of the night light, so that the wick will be properly centered. The wax or other fuel is then poured in carefully so as not to displace the now centered wicking and then its upper end has to be disconnected from the supporting cross bar, which is then removed.

Under our invention we obviate all these difficulties and secure a superior light.

Referring to the drawings, Figure 1 is a vertical sectional view of a night light embodying our invention in its complete form; Fig. 2 is a view similar to Fig. 1, showing the night light in operation; Fig. 75 3 is a view similar to Figs. 1 and 2, showing the condition and position of the parts after the light has been used, extinguished and has again become cold; Fig. 4 is a plan view.

In the drawings we have illustrated the container of the light as an ordinary glass tumbler. This is so that it may be used for household purposes after its use as a night light has ceased because of the consumption of all the wax or fuel. It will of course be understood that any suitable container may be used, glass, metal, asbestos, or other suitable substance, may be employed and that its shape is immaterial.

In the drawings 1 represents the container or receptacle in this case a tumbler.

2 represents the fuel, usually wax, paraffin or any equivalent substance, which we prefer should not more than about two-thirds fill the container, so that it shall act as a wind shield to prevent the extinguishment of the flame by air drafts. 3 repre-

sents a candle made of inflammable material, usually wax, and provided with a suitable wick 4, which is supported at its lower end by a suitable support 5, which we prefer 5 to make of metal. It is not essential that the support be made in the form of a socket, as shown, because any suitable support, irrespective of its shape, having, perhaps, a centrally located pin adapted to en- 10 ter the lower end of the candle may be used, in short, any device for supporting the candle is all that is necessary.

The candle 3 is made of wax, or equivalent material having a higher melting point 15 than the body of wax or fuel 2 in the container, so that it will not melt so readily as the fuel, on the contrary, will retain its form and solidity during the burning of the light almost, but not quite to the top of the 20 molten fuel, so that the wick will permanently have a rigid and substantial support almost, if not quite to the surface of the melted fuel as illustrated in Figs. 2 and 3. By this means the wick will always be 25 reliably supported and will be prevented from toppling or being blown over. Thus it will always maintain an upright position, its upper end projecting substantially above the upper surface of the wax, whether 30 melted or solid, and irrespective of its level in the container.

It will be noted that the defects in lamps as heretofore made are avoided, that is to say, there is no necessity for a metallic, 35 broom straw, or other support for the wick. There is no possibility that a considerable length of the wick shall be left unsupported because of the melting of the wax or fuel, thus making it liable to subside into and be 40 extinguished by the molten wax and lastly, there is no occasion for the annoying and time-taking devices above described for centering and supporting the wick during the manufacture of the light because all that is 45 necessary in the manufacture of our lights is to pour the desired quantity of the wax or other fuel into the container and then while it is still soft, the little candle handled by its upwardly projecting wick, may be easily 50 and quickly introduced into the melted wax and pushed downwardly until the support rests upon the bottom of the container. It is not necessary to wait for the cooling of the wax or fuel because the support 5 for the 55 candle will maintain it in a properly upright and centered position.

Figs. 1, 2 and 3 correctly represent the successive stages in the operation of our improved device, that is to say, Fig. 1 shows the finished lamp as presented to the public, Fig. 2 shows the lamp after it has been burning for some time. It will be noted that the candle 3 has burned down somewhat and that a part of the fuel or wax has also been 65 consumed, the level of the melted wax being

represented by 6 and the level of the unmelted wax by 7. The candle, however, which melts at a higher temperature than the wax or fuel 2, has an unmelted and wick supporting portion 8 projecting upwardly 70 into the molten wax or fuel 2, and this unmelted, upwardly projecting end of the candle extends to within a sixteenth of an inch or thereabouts of the upper surface 6 of the melted wax and this relation of the 75 parts extends throughout the entire building of the light, so that the wick has a permanent, reliable support practically up to the level of the molten wax, so that it is impossible for it to sag or subside into the 80 molten fuel.

The difference in melting point between the wick supporting candle and the body of the fuel need be sufficient only to insure the slower melting of the candle, so that it shall 85 remain as a suitable support for the wick and the difference in melting point may, obviously, be regulated so as to cause the candle to maintain substantially its original form and solidity for a distance to reach 90 slightly above or even with or slightly below the surface of the molten fuel, as may be preferred, the latter relation being the one illustrated in the drawings. We have found that while there is no essentially necessary degree of difference in melting point, 95 yet that a differentiation of from 20 to 30 degrees is useful.

Having described our invention we claim:

1. As a complete, unitary article of manufacture, a night light comprising a container, a body of fusible fuel immovably held in the container, and a wick-supporting candle having a higher melting point than the fusible fuel, molded in and immovably held by the fusible fuel. 100

2. As a complete, unitary article of manufacture, a night light comprising a container, a body of fusible fuel immovably held in the container, a wick-supporting candle having a higher melting point than the fusible fuel, molded in and immovably held by the fusible fuel, and a non-floating support for the lower end of the candle. 105

3. As a complete, unitary article of manufacture, a night light comprising a translucent container, a body of fusible fuel immovably held in and only partially filling the container, a wick-supporting candle having a higher melting point than the fusible fuel and immovably molded in it, and a non-floating support for the lower end of the candle resting upon the bottom of the container and immovably embedded in and held by the body of fusible fuel. 115

4. As a complete, unitary article of manufacture, a night light comprising a translucent container adapted to independent and subsequent use, a body of fusible fuel which only partially fills the container and is im- 120 125 130

movably held therein, and a wick-supporting candle molded in and immovably held by the fusible fuel.

5. As a complete, unitary article of manufacture, a night light comprising a container adapted to independent and subsequent use, a body of fusible fuel which only partially fills the container and which is immovably held by it, and a wick-supporting

candle having a higher melting point than 10 the fusible fuel molded in and immovably held by the fusible fuel.

In testimony whereof we have signed our names to this specification.

CHARLES H. HAWKINS.

CHARLES W. SMITH.
